SERIES SOCKET WITH REMOVABLE ELEMENTS

Raymond W. Corwin, Haddonfield, N. J., assignor
to Benjamin Electric Manufacturing Company,
Des Plaines, Ill., a corporation of Illinois

Application May 5, 1930, Serial No. 449,781

5 Claims. (Cl. 173—344)

This invention relates to electric light sockets and has special reference to electric light sockets having removable elements.

- More particularly, this invention relates to an electric light socket having a base comprising a plurality of sections with the wiring terminals on one section and the side and center contacts attached to other of the sections and electrically connected to the wiring terminals. Contact plates are attached to both the side and center contacts which, when the socket is assembled, engage contacts carried in the outer sections with the wiring terminals and connected therewith.
- An object of this invention is to provide a socket comprising a plurality of sections with the wiring terminals attached to one section and one or more of the other sections carrying the lamp contacts so that they may be removed and replaced in the event the contacts attached thereto become damaged by arcing or from any other cause without necessitating disconnecting the lead wires from the wiring terminals.

Where several lamps are connected in series in a circuit, such as a 600 volt circuit, the lamp contacts of the socket are frequently damaged due to an arc being formed between the socket contacts and the lamp contacts, particularly between the center contacts. In the ordinary socket when such damage occurs it is necessary to disconnect the wires from the wiring terminals before dismantling the socket and replacing the damaged parts. In a socket embodying the present invention, if a contact becomes damaged, it is merely necessary to replace the section of the socket carrying the contact with a new section without disconnecting the wiring terminals from the wires or the socket from the fixture supporting member to which it is attached.

The sections of the present socket are held in assembled position by two screws so that to replace a damaged section it is only necessary to remove the two screws, replace the section with a new one and replace the screws, which all may be done while the lead wires are connected to the wiring terminals of the socket. Thus, the more frequently damaged and least expensive parts may be easily and inexpensively replaced.

A further object of the present invention is to provide a socket in which the possibility of arcing is reduced to a minimum and any arcing that might occur is confined to the lamp cavity.

The wiring terminals to which the lead wires

are connected are so far removed and protected from the lamp contacts that there is no possibility of the wiring terminals or lead wires connected thereto being burned or damaged by arcing between the lamp and socket contacts. In order to prevent arcing between the conductors connecting the contacts to the wiring terminals the conductors are extended through separate openings in the intermediate base section of the socket. Thus the possibility of any arcing is confined to the lamp cavity where the arc will affect only parts that may be easily removed. To reduce the arcing in the lamp cavity between the side and center contacts the center contact is widely spaced from the shell.

A still further object of the present invention is to provide a socket in which the wiring terminals are protected from the heat caused by the lamp in the socket. The intermediate base section which separates the wiring terminals from the lamp cavity is made of heat insulating material, and there is very little air circulation to carry heat to the wiring terminals by convection of the air. Furthermore the distance between the contacts and the wiring terminals allows much of the heat that would be carried to the wiring terminals to dissipate.

Further objects and advantages of the present invention will be more readily apparent from the following detailed description, together with the accompanying drawing, in which latter:

Figure 1 is an elevational view of a socket embodying the present invention attached to a fixture supporting member;

Fig. 2 is a top plan view of the socket and cushion member attached thereto taken on the line 2—2 of Figure 1;

Fig. 3 is a central vertical cross sectional view of a socket embodying the present invention;

Fig. 4 is a bottom plan view of the upper section of the socket taken on the line 4—4 of Fig. 3;

Fig. 5 is a top plan view of the middle section of the socket taken on the line 5—5 of Fig. 3;

Fig. 6 is a top plan view of the bottom section of the socket showing the shell contact and contact plate connected therewith.

Referring more particularly to the drawing, the present construction comprises a socket having a top section or base 2, a middle section or base 3 and a bottom section or base 4, each made of insulating material. Terminal screws 5 are threaded into terminal plates 6

which are held in recesses in the bottom side of the top section 2 by means of screws 7. The screws 7 are inserted through the top of the top section 2 and thread into threaded openings provided therefor in the terminal plates 6. The terminal plates 6 and the screws 7 hold the spring contacts 8 in position in the top section 2. The spring contacts 8 are of the type such as are used in an ordinary knife switch. The lead wires for connection with the terminals 5 are inserted from the top of the top section 2 through holes 9b therein positioned at each end of the groove 9a and then connected to the wiring terminals by means of the wiring terminal screws 5.

The middle section or base 3 of the socket is preferably made of heat insulating material so as to prevent the heat in the lamp cavity from affecting the wiring terminals. This section 3 carries a center contact 9 on the bottom thereof and a contact blade 10 on the top surface thereof. The center contact 9 is substantially V-shaped, having arms 11 and 12 with a hole adjacent the end of arm 11. The contact blade 10 has a threaded opening adjacent one end. A screw 13 is inserted through the opening in the arm 11 of the center contact 9 up through a central opening 13a in the middle section 3 and is threaded into a threaded opening in the contact blade 10 which lies in a groove provided therefor in the top of section 3. The central opening 13a is only slightly larger than the size of the screw 13 so as to prevent the heat in the lamp cavity from affecting the wiring terminals. When thus assembled the upright portion of the contact blade 10 is adapted to engage one of the spring contacts carried in the upper section 2 of the socket, and the center contact secured to the middle section 3 extends partly downward to form a resilient contact.

The bottom section or base 4 of the socket is in the nature of a ring having an opening in the center thereof in which is positioned a shell contact 14. Various types of bottom sections or bases may be used with the same upper sections or bases, depending upon the purpose for which the socket is to be employed and the size of lamp to be used. The shell contact 14 is crimped to a shell flange 15, for securing the shell contact 14 to the bottom section 4. A contact blade 16, extending substantially straight upward, is attached to the shell flange 15, being preferably formed integrally therewith. The shell flange is eyeletted to the bottom section 4 of the socket so that the contact blade 16 will extend up through an opening 16a of substantially the same size as the blade 16 and engage with the other spring contact 8.

The three sections of the socket, 2, 3 and 4, are held together by means of screws 17, which are inserted from the bottom of section 4 and extend up through the middle section 3 and thread into threaded members permanently secured to the top section 2. Thus, to remove either the middle section 3 or the bottom section 4, it is only necessary to remove the screw 17, replace the section with a new section and then replace the screws. All this may be done without disconnecting the wires from the wiring terminals.

Figure 1 shows the socket 1 assembled in a fixture. A reflector 18, having an annular flange 19 is positioned between the usual reflector securing flanges 20 and 21, which flanges are fastened to a conduit 22. The socket 1 is fastened

to a cushion member 23 by screws 24, and this cushion member is, in turn, attached to the fixture securing means comprising the conduit 22 and the flanges 20 and 21 by screws 25. When so attached, the fixture is ready for use upon the insertion of a lamp.

As shown in Figure 1 it would entail a great deal of effort to replace a damaged contact if it were necessary to dismantle the whole fixture in order to replace the damaged member. With the present invention such is unnecessary and any damaged member may be quickly replaced with a minimum effort.

In the claims where I have used the expression "quick detachable contacts", it is to be understood as defining a contact having a quick detachable engagement and disengagement with respect to its cooperating contact blade.

While I have shown and described but one embodiment of the present invention, it will be apparent to those skilled in the art that various modifications thereof may be made without departing from the spirit and scope of this invention, and, therefore, I wish to be limited only by the prior art and the scope of the appended claims.

I claim:

1. An electric lighting fixture comprising three sections with one section lying between the other two, wiring terminals attached to one of the outer sections and connected to spring contacts carried in said outer section, a center contact attached to the inner section and a shell contact adapted to receive a lamp, attached to the other outer section, contact blades secured to the center and shell contacts for engaging with said spring contacts, said contact blade secured to said shell contact passing through an opening in said inner section whereby said outer section carrying said shell contact and contact blade secured thereto may be detached from said socket without affecting the other two sections, and means for fastening the three sections together.

2. A high voltage series socket construction comprising a first insulating base portion having a pair of recesses therein, a pair of quick detachable contacts in said recesses, a second insulating base portion covering the contacts in said recesses, a center contact mounted on said second base portion, a blade mounted on said second base portion and electrically connected with said center contact extending into one of said recesses and engaging one of said quick detachable contacts, a third base portion, a shell contact mounted thereon, and a blade electrically connected with said shell contact, mounted on said third base portion, extending into the other of said recesses and engaging the other of said quick detachable contacts.

3. A high voltage series socket construction comprising a first insulating base portion having a pair of recesses therein, a pair of quick detachable contacts in said recesses, a second insulating base portion covering the contacts in said recesses, a center contact mounted on said second base portion, a blade mounted on said second base portion and electrically connected with said center contact extending into one of said recesses and engaging one of said quick detachable contacts, a shell contact, said second base portion having a restricted blade passage therethrough, and a blade electrically connected with said shell contact passing through said restricted opening and extending

- into the other of said recesses and engaging the other of said quick detachable contacts, said shell contact being provided with an outwardly extending flange to which the blade is secured.
4. A high voltage series socket construction comprising a wiring base and contact member, a pair of wiring terminals mounted thereon, a pair of quick detachable contacts also mounted thereon in electrical connection with said wiring terminals, respectively, said wiring base having a pair of recesses therein for said contacts, respectively, an insulating cover member extending across said recesses, a center contact mounted on said cover member, a contact blade mounted on said cover member electrically connected with said center contact and engageable with one of said quick detachable contacts, an annular shell contact, a blade electrically connected with said shell contact and extending through an opening in said cover member into engagement with the other of said quick detachable contacts, the electrical connection between the blade and the shell contact lying substantially outside the cylindrical surface of the annular shell contact, and a separate insulating sleeve surrounding said shell contact to which said shell contact and its associated blade are secured.
5. A high voltage series socket construction comprising a wiring base and contact member, a pair of wiring terminals mounted thereon, a pair of quick detachable contacts also mounted thereon in electrical connection with said wiring terminals, respectively, said wiring base having a pair of recesses therein for said contacts, respectively, an insulating cover member extending across said recesses, a center contact mounted on said cover member, a contact blade mounted on said cover member electrically connected with said center contact and engageable with one of said quick detachable contacts, an annular shell contact, a blade electrically connected with said shell contact and extending through an opening in said cover member into engagement with the other of said quick detachable contacts, the electrical connection between the blade and the shell contact lying substantially outside the cylindrical surface of the annular shell contact, and a separate insulating sleeve surrounding said shell contact to which said shell contact and its associated blade are secured.
